UNITED STATES PATENT OFFICE.

JULES E. ROEMHELD, OF CHICAGO, ILLINOIS, ASSIGNOR TO GREAT LAKES DREDGE AND DOCK COMPANY, OF CHICAGO, ILLINOIS, A CORPORATION OF NEW JERSEY.

CAR-DUMPER.

1,360,583.

Specification of Letters Patent.

Patented Nov. 30, 1920.

Application filed February 18, 1918. Serial No. 217,939.

To all whom it may concern:

Be it known that I, JULES E. ROEMHELD, a citizen of the United States, residing at Chicago, in the county of Cook and State of Illinois, have invented certain new and useful Improvements in Car-Dumpers, of which the following is a specification.

Car dumpers of the class to which my invention relates are constructed to receive an open-topped coal car, or the like, of any construction, and elevate it to the height required and tilt or overturn it sidewise dumping its contents into a suitable chute which conveys the material to a vessel to be loaded, a storage dump, or the like. The car dumpers heretofore constructed consist of an elevator adapted to receive a single car and to raise and dump it, an incline or approach up which the cars to be dumped must be driven to reach the elevator, and a chute which is pivoted to the frame of the apparatus so that it may be lowered to a proper inclination to secure the flow of material dumped therein, and to discharge the material into the vessel or the like to be loaded, and raised out of the way when the loading operation is completed. The machinery and apparatus involved in dumpers of this character is complicated and difficult and expensive to install, maintain and operate. It is the purpose of my invention to provide a car dumper of relatively simple construction, which is inexpensive to construct, maintain and operate. For this purpose I provide a rocking or tilting frame having mounted thereon tracks or supports which receive a car to be dumped, and a chute, the flared receiving end of which is so arranged relative to the tracks that when the pivoted structure is rotated to the dumping position the load of the car is discharged into the chute and by the latter conducted to the vessel to be loaded. The construction and movement of the tilting frame are substantially like those of the well-known bascule bridge.

In the accompanying drawings I have shown and in the following specification described two somewhat similar but specifically different constructions embodying my invention. It is to be understood, however, that the specific disclosure is for the purpose of exemplification only, and that the scope of the invention is defined in the following claim in which I have endeavored to dis-

tinguish it from the prior art so far as known to me without, however, relinquishing or abandoning any portion or feature thereof.

In the drawing, Figure 1 is a section on the line 1—1 of Fig. 3 looking in the direction of the arrows showing the preferred form of the apparatus in elevation in the position which it occupies when a car is received thereon; Fig. 2 is a similar view of the same construction, the parts, however, being shown in the position which they occupy when a vessel is being charged; Fig. 3 is a section through the line 3—3 of Fig. 1 on a plane perpendicular to the latter showing the parts in the same position as in Fig. 1; Fig. 4 a view similar to Fig. 1 but of a modified form of the invention; Fig. 5 is a section parallel to the plane of Fig. 1 on the line 5—5 of Fig. 3 on an enlarged scale showing more particularly the means for holding the car in place on the rocker frame; and Fig. 6 a detail section on the line 6—6 of Fig. 5.

Each part is designated by the same reference character wherever it occurs throughout the several views.

Referring first to Figs. 1, 2 and 3 and the preferred form of the invention shown therein, the stationary supporting frame is shown as comprising bifurcated standards 6, 6, spaced a suitable distance apart and supporting at their upper ends bearings 7, 7 in which the trunnions 8, 8 of the tilting or rocking frame are received. Obviously, however, the particular form of the frame is immaterial if it provides suitable supports for the tilting frame and associated mechanism. I have shown it as so located with reference to the edge 9 of a dock from which vessels 10 are to be loaded that when the rocking frame is tilted or swung to a position to dump a car the discharge end of the chute will be properly located with reference to the vessel to be loaded.

The rocking or tilting frame may be constructed of the usual structural materials of any suitable form and dimensions which will provide the required strength. In the specific form of mechanism illustrated in Figs. 1 to 3, inclusive, the frame comprises a pair of similar spiders 11 arranged upon opposite sides of the apparatus, the members 11^a of which radiate with respect to the axis of the frame, and certain of which support at

their outer ends a rack 12 which is concentric with the axis of the frame. Said rack is preferably braced by the truss elements 13. A transverse shaft 14 (see dotted lines 5 Fig. 3) is journaled in the standards 6 at the proper distance from the axis of the tilting frame and carries at its ends pinions 15 which mesh with the respective racks upon the tilting frame. By rotating the shaft 14 10 and the pinions thereon, the arcuate racks are operated to swing the frame. Any suitable means may be employed for rotating the shaft 14, and for this purpose I have shown it as equipped with a gear wheel 16 15 meshing with speed reducing gears 17, 18, driven by an electric or other suitable motor 19. These elements may be mounted in any suitable manner upon one of the standards 6. The chute 20 and car platform or support 21 are also connected to the spiders by suitable means, struts and frame work such, for example, as shown in Figs. 1 and 2. As seen in Fig. 3 the chute comprises a flared or funnel shaped portion 22, which is widest 25 as at 23 at its mouth or opening, where it is equal to or greater than the length of the longest car in connection with which the dumper is intended to be used. The mouth or opening is also of sufficient height relatively to the width of the cars to be dumped 30 as to receive the entire contents thereof when the rocking frame is tilted.

The car platform is inclosed in a rectangular frame or cage, the side members 35 of which on one side are substantially in the plane of the bottom of the chute, and the other side members 25 suitably spaced therefrom to admit between the two sets of side members the body of the car 26 to be dumped. The car platform 21 is provided 40 with tracks 27 to receive the cars, and when the tilting frame is in the position shown in Fig. 1 these track sections register with and form substantial continuations of stationary 45 tracks arranged in the usual manner upon the ground and from which cars may be pushed upon the platform of the frame. Preferably in order to fix the position of the track sections 27 when in the normal 50 position shown in Fig. 1, I construct in the ground or immediately beneath the position of said tracks, foundations or supports 28, and provide platform 21 with a supporting framework 29 of the proper height so that 55 when the framework rests upon the foundations the track sections upon the platform are at the same level as the ground tracks.

It is obviously necessary that when the 60 frame is tilted to dump the cars means be provided for locking the cars against the tilting movement relative to the rocking frame. Any suitable means may be provided for this purpose, and I have illustrated in the drawings clamp members 30 which 65 are arranged to slide vertically in the side

posts 24, 25. Any desired number of these clamp members may be employed, though in the particular construction shown I have illustrated them as four in number. They are arched or cut away in the center, as at 70 31, so that their edges 32, 32 may engage the upper edges of the side walls of the car, and at the same time their central portions escape the load in case the latter is heaped 75 above the walls of the car. These clamping members must be locked in place when the frame is tilted and must be capable of releasing the car when the frame is in normal position. With this in view I have shown the clamping members as carried on pillars 80 or followers 33, sliding in the posts or standards 25, which are made hollow for the purpose, said pillars being each provided with an inwardly extending arm 34, braced as at 85 35, and carrying at its free end, which is substantially over the center of the car when the latter is in position on the frame, an upright 36. In normal position the clamps are raised as in Fig. 5 by contact of the lower 90 ends of the pillars with supports 33^a.

As shown more particularly in Fig. 5 the clamping members are each provided at one edge with a locking device which is shown in the form of a pawl 53 carried by the clamping member and engaging a ratchet 95 54 upon the adjacent post 25. The pawl is provided with trunnions 56 which are pivoted in ears 57 of a bracket 58 which is bolted to the upper edge of the clamping member. The corner of the clamping member is cut away in an obvious manner to make room for the barrel 59 of the pawl, the curved seat so formed constituting a bearing for the pawl. The pawl is extended on the opposite side of its trunnions to form a 100 pair of arms 60, 60 arranged on opposite sides of the clamp (see Fig. 6) which are counterweighted at their lower ends as at 105 61 to such an extent that the counterweights control the position of the pawl. When 110 the rocking frame is in its normal position with the car upright the counterweights hold the pawl out of engagement with the rack but when the device tilts to the dumping position the weights throw the pawl into 115 engagement with the rack and hold the clamping member firmly in engagement with the edges of the car. Preferably the edge 62 of the clamping member opposite the pawl is received in a groove 63 of a guide 64 secured to one of the uprights or posts 24. Lugs 65 may also be formed upon the 120 clamping member to embrace the opposite sides of the car and limit sidewise movement. The coal chute may be rigid throughout, but preferably and in order to more widely distribute the coal as it flows from the chute, the latter is provided with a swinging end section 37 which is pivoted at 125 38 to swing in a vertical plane, the co-operat- 130

ing ends of the main body of the coal chute and of the pivoted section being curved at 39, 40, respectively, concentric with the pivot and caused to overlap so that there 5 may be no opening between the sections. The rack 41 on the pivoted section is engaged by a pinion 42 on the body of the chute, the latter being driven in any suitable manner, as for example, by a reversing 10 electric motor 43, the current to which may be supplied from any suitable source and controlled wherever desired. The outer end of the pivoted section is provided with a gate 66 which is kept closed during the 15 tilting operation until the section is in the proper position to discharge the coal or the like. Then the gate is opened to permit the coal in the chute to flow into the vessel to be loaded. As these gates are well known in 20 constructions of the kind it is considered unnecessary to describe them in detail.

It is desirable also in order to reduce the power necessary to operate the device to a minimum to provide a counter-weight 44 on 25 the rotating frame, which is preferably of such magnitude as to nearly counter-balance the construction when the latter carries a loaded car.

From the foregoing description it will be 30 understood that the construction is normally in the position shown in Fig. 1, and in which it is prepared to receive a car from the tracks leading thereto. When the car is run onto the tracks on the platform the motor 35 is started to drive the shaft 14 and thereby to cause the pinions on said shaft to rotate the rocking frame through the racks thereon. As the frame tilts the clamp drops to locking position and holds the car securely, 40 as heretofore described, during the succeeding movement of the rocking frame and until the latter returns to normal position.

In the second form of the invention chosen 45 for illustration the chute and means for holding the car are the same as above described, but the rocking frame instead of being mounted upon a stationary pivot is mounted upon a pair of rockers 45 which travel upon tracks 46 preferably arranged 50 substantially at dock level. The rocking

frame is provided at a point concentric with the rockers with a rotary shaft 46 upon the ends of which are pinions 47 which travel along horizontal racks 48 mounted upon frames 49 of suitable construction and 55 strength arranged parallel to the tracks 46 on opposite sides of the tilting or rocking frame. Obviously, by rotating the shaft and its pinions 47 the latter may be caused to travel along the horizontal racks and 60 thus rock the frame. The shaft may be rotated by any suitable or well-known means, as for example by an electric motor 50 mounted upon the rocking frame and connected to the shaft by reducing gearing 51, 65 52. In this form of the invention the rocking frame not only rocks but travels in tilting toward the end of the pier or dock. In other respects, however, the operation as well as the construction is, or may be, similar 70 to that of the preferred form of the invention previously described.

It will now be evident that by my invention I have produced a greatly simplified form of car dumper which may be readily 75 operated and controlled with a minimum of labor. There are no cables or the like to wear out and require replacement, and the cost of maintenance as compared to previous devices for the same purpose is low. 80 Furthermore, the operating expense is relatively low for the reason that there is but the one structure or framework to be moved, and this is substantially counter-balanced so that heavy machinery and engines 85 for operating it are dispensed with.

I claim:

In a device of the class described, a stationary frame, a rocking frame pivoted thereon adapted to swing through an arc 90 of more than ninety degrees, a chute rigid therewith, means mounted on the rocking frame for locking a car on a frame adjacent the receiving end of the chute, rack sectors also mounted on the rocking frame concentric with the axis thereof, pinions for engaging the said racks, and means for rotating the pinions.

JULES E. ROEMHELD.
